UNITED STATES PATENT OFFICE.

GEORGE A. GAGE, OF CHICAGO, ILLINOIS.

VENEER COILING AND NAILING MACHINE.

SPECIFICATION forming part of Letters Patent No. 628,085, dated July 4, 1899.

Application filed July 30, 1898. Serial No. 687,249. (No model.)

To all whom it may concern:

Be it known that I, GEORGE A. GAGE, a citizen of the United States of America, and a resident of Chicago, in the county of Cook and State of Illinois, have invented certain new and useful Improvements in Veneer Coiling and Nailing Machines, of which the following is a specification.

My invention relates to veneer-package-forming machines, and has particular reference to coiling and nailing the veneering to form cylindrical packages.

The main object of my invention is to provide a machine which will facilitate the above-mentioned operation. To this end I provide a nailer operating in conjunction with an improved collapsible coiling-drum.

The objects of the particular features of construction hereinafter claimed will be understood from the following description, with reference to the accompanying drawings, in which—

Figure 1 is a front elevation of a machine constructed according to my invention. Fig. 2 is a side view of the friction-pulleys 12 and 18, showing the position of the depression 12" when the pulleys are out of frictional contact. Fig. 3 is a top plan of the machine, showing mainly the mechanism for operating the nailer, and omitting other details of the machine.

Fig. 4 is an end elevation. Fig. 5 is a vertical section through the lever 4 and shafts within same on the line xx of Fig. 1. Fig. 6 is a horizontal section through the lever 4 and shafts on the line yy of Fig. 5. Fig. 7 is a vertical section through the sleeve 7 and shafts within same on the line zz of Fig. 1. Fig. 8 is a vertical section of the casing 31, showing the inclosed mechanism of the nailer. Fig. 9 is a side view of the cam 34 of the nailer. Fig. 10 is a perspective view of a metal nailing-strip adapted for use with my nailer.

The machine consists, mainly, of a collapsible drum mounted on the shaft 2 and having an umbrella action operated by the lever 4 and a nailer traveling lengthwise of the drum. The shaft 2 is hollow, slotted at 2' and 2", and journaled in the members 13, 15, and 16 of the frame. The shaft 1 is longitudinally movable in the shaft 2 and has a pin 1' projecting through the slot 2' into an annular groove 3' in the sleeve 3. The sleeve 3 is

loose on the shaft 2 and is pivoted to the lever 4 at 4'. The lever 4 is provided with a handle at its free end and is pivoted to the frame at 5. The sleeves 6 of the drum are rigid on the shaft 2, and the sleeves 7 are longitudinally movable thereon and are connected to the shaft 1 by a pin 1", passing through the slot 2". Arms 8 are pivoted at 10 to the inner ends of the sleeves 6 and 7 and at their outer ends, at 10, to the segments 11 of the drum.

The shaft 2 is driven by the friction-pulley 12, which is rigid thereon. The pulley 12 is driven by frictional contact with the pulley 18, which is rigidly mounted on the shaft 19 of the driving-pulley 22, journaled in the member 13 of the frame. The pulley 12 is at rest when the depression 12" is presented to the pulley 18, as shown in Fig. 2. To start the pulley 12, the operator depresses the step 20' of the lever 20, and the tooth 20', engaging with one of the teeth 12' on the pulley 12, will turn same sufficiently to bring it into frictional contact with the pulley 18, and thus cause same to make a single revolution. The lever 20 is slightly flexible at the part between the fulcrum 21 and the spring 21'. The lever 20 is fulcrumed on the frame 21 and is normally held in the position shown by the spring 21'.

When the lever 4 is pulled toward the drum, the same, operating on the sleeves 7 through the shaft 1, will collapse the drum. Before the drum is collapsed at the end of each revolution the nailer is brought into operation, the operator depressing the step 26' of the lever 26. The lever 26 is fulcrumed at 25' on the member 25 of the frame, and its arm 26', acting against the sheave 23, throws its clutch 23' into engagement with the pulley 22 and turns the sheave so as to wind up enough of the cable 27 to carry the nailer the required distance along the drum. This is done by a single revolution of the sheave 23, which is then thrown out of engagement with the pulley 22 by suitable mechanism, such as a cam 23" on the sheave 23, having contact with an arm 14' on the member 14 of the frame. The fulcrum 25' is in a slightly-higher horizontal plane than the free end of the arm 26', thus permitting the movement of the sheave 23 by the action of the cam 23". The cable 27 is

secured at one end of the sheave 23, passes over the sheaves 28 and 29, and has a weight 30 for bringing same back into the position shown in Figs. 1 and 3 when the pulley 23 is 5 out of engagement with the pulley 22. The sheave 28 is journaled in the position shown on a suitable support, which is not shown in the drawings.

The casing 31 of the nailer is rigidly secured to the box 35' by the arms 31' and has a plunger 32 vertically movable therein and pressed normally downward by the spring 33, one end of which is seated in the casing and the other end in the plunger. A shoulder 34' on the plunger has contact with the cam 34 for raising the plunger. The striking member 32' is secured in the end of the plunger by the set-screw 32''. The cam 34 is rigid on the shaft 35. The shaft 35 is also journaled in the boxes 35' and 35'', which are slidingly mounted on the rods 46''. The rods 46'' are secured to the members 46' and 47' of the frame. A sleeve 27' is loose in the shaft 35 and is secured to the cable 27. The pulley 37 is rigid on the shaft 35. The clutch 37' is feathered to the shaft and normally urged into engagement with the pulley 37 by the spring 35''. The member 37'' is rigid on the member 46' of the frame and throws the clutch 37' out of the engagement with the pulley 37 when the nailer is in the position shown. The pulley 37 is driven by the belt 38 over the driving-pulley 40, which is journaled in a suitable support. (Not shown in the drawings.) The idler 39 is journaled in bearings 34, sliding on the members 44 of the frame in similar manner as the boxes 35' and 35'' slide on the rods 46'', the members 44 being supported by the members 45 and 46 of the frame. A sleeve 43' is loose on the shaft of the idler 39 and is secured to the cable 43, which passes over the sheave 41 and has a weight 42 at its free end. The idler 39, acted upon by the weight 42, preserves the proper tension on the belt 38. A guide 36 is secured to the casing 31 and serves to hold a pronged metal nailing-strip in proper position to be operated upon by the nailer in securing same to the veneer package. A presser-roll 48 is pivoted to the rod 49, which is slidingly supported in the member 47' of the frame. Weights 50 are secured to the rod 49 and keep the roller in contact with the veneering while same is being coiled upon the drum.

55 In operating the machine a sheet of veneering is fed from the front upon the drum with its forward edge in the groove 11' in one of the segments 11 when in the position shown in Fig. 4. The operator then starts the pulley 12 by means of the lever 20, and the drum is thereby caused to make a single revolution, coiling the veneering so that its ends overlap. The outer lap of the coil is then under the nailer, the drum having stopped at 60 the end of its revolution through the position of the recess 12'' in the pulley 12. The operator now throws the sheave 23 into engagement

with the driving-pulley 22 by means of the lever 26, and thereby starts the nailer on its course across the drum, a nailing-strip 51 having been previously inserted in the guide 36 with its frontend projecting under the nailer. As soon as the clutch 37' is free from the member 37'' the clutch engages the pulley 37 and starts the operation of the nailer. The spring 35'' now forces the clutch 37' into engagement with the pulley 37, thereby causing the shaft 35 to revolve, causing the cam 34 by action against the shoulder 34' to raise the plunger at each revolution, the spring 33 driving 80 same down upon the nailing-strip, and thus driving the prongs 51' into the material of the package. When the nailer has traveled to its limit toward the member 47 of the frame, the sheave 23 is disengaged from the pulley 85 22, as before described, and the action of the weight 30 then draws the nailer back to its former position until its clutch 37' again comes in contact with the member 37'', whereby the pulley 37 is caused to run loose on its 90 shaft and stop the operation of the nailer. The drum is now collapsed by means of the lever 4, and the member 16 by means of the handle 16' is tilted away from the shaft 2 on its pivotal connection at 16'', so as to permit 95 the removal of the veneer package.

It is plain that the details of construction of my device may be altered in numerous ways without departing from the spirit of my invention. I do not therefore confine myself 100 to such details.

In specifying a traveling nailer in the claims I refer to its movement along and across the periphery of the drum or package thereon.

What I claim as my invention, and desire to secure by Letters Patent, is—

1. In a veneer coiling and nailing machine, the combination of a suitable frame therefor; a rotary collapsible drum journaled in said frame; a traveling nailer supported by said frame, and operative in a course along or across the periphery of the drum; means for collapsing, expanding and rotating, said drum; a rotary shaft supported in sliding 110 bearings, traveling with said nailer; means for carrying the nailer and shaft along said course, and simultaneously rotating the shaft; and a connection between said nailer and shaft whereby the nailer is operated through 115 the rotation of the shaft.

2. In a veneer coiling and nailing machine, the combination of a suitable frame therefor; a rotary collapsible drum journaled in said frame; a traveling nailer supported by said 125 frame, and operative in a course along or across the periphery of the drum; means for collapsing and expanding said drum; means for intermittently revolving said drum; a rotary shaft supported in sliding bearings, 130 traveling with said nailer; means for carrying the nailer and shaft along said course, and simultaneously rotating the shaft; and a connection between said nailer and shaft

whereby the nailer is operated through the rotation of the shaft.

3. In a veneer coiling and nailing machine, the combination of a suitable frame therefor; 5 a rotary collapsible drum journaled in said frame; a traveling nailer supported by said frame, and operative in a course along or across the periphery of the drum; means for collapsing and expanding said drum; means 10 for intermittently revolving the drum; a rotary shaft supported in sliding bearings traveling with said nailer; means for carrying the nailer and shaft along said course, and simultaneously rotating the shaft, while the 15 drum is at rest; and a connection between said nailer and shaft whereby the nailer is operated through the rotation of the shaft.

4. In a veneer coiling and nailing machine, the combination of a suitable frame therefor; 20 a rotary collapsible drum journaled in said frame; said drum comprising a plurality of segments connected together in such manner as to uniformly approach or recede from a common center; a traveling nailer, supported 25 by said frame, and operative in a course along or across the periphery of said drum; means for collapsing and expanding said drum; means for rotating said drum; a rotary shaft supported in sliding bearings, traveling with 30 said nailer; means for carrying the nailer and shaft along said course, and simultaneously rotating the shaft; and a connection between said nailer and shaft whereby the nailer is operated through the rotation of the shaft.

35 5. In a veneer coiling and nailing machine, the combination of a suitable frame therefor; a rotary collapsible drum journaled in said frame; said drum comprising a plurality of segments connected together in such manner 40 as to uniformly approach or recede from a common center; a traveling nailer, supported by said frame, and operative in a course along or across the periphery of said drum; means for collapsing and expanding said drum; a 45 rotary shaft supported in sliding bearings traveling with said nailer; means for carrying the nailer and shaft along said course, and simultaneously rotating the shaft, while the drum is at rest; and a connection be-

tween said nailer and shaft whereby the 50 nailer is operated through the rotation of the shaft.

6. In a veneer coiling and nailing machine, the combination of a suitable frame therefor; 55 a rotary collapsible drum journaled in said frame; means for collapsing, expanding, and rotating said drum; a nailer mounted on a rotary shaft supported in sliding bearings having a course along or across the periphery of the drum; means for normally urging 60 said nailer toward one end of the drum; means for carrying same toward the other end, and simultaneously operating same; and a connection between said nailer and shaft, whereby the nailer is operated through the 65 rotation of the shaft.

7. In a veneer coiling and nailing machine, the combination of a suitable frame therefor; 70 a rotary collapsible drum journaled in said frame; means for collapsing, expanding, and rotating said drum; a nailer mounted on a rotary shaft supported in sliding bearings having a course along or across the periphery of the drum; means for normally urging 75 said nailer toward one end of the drum; means for stopping its operation at said end; means for carrying same toward the other end, and simultaneously operating same; and a connection between said nailer and shaft, whereby the nailer is operated through the 80 rotation of the shaft.

8. In a nailing-machine, the combination of a suitable frame therefor; a plunger support or casing 31, slidably mounted on the frame; a rotary shaft movable with said support in 85 sliding bearings on said frame; a plunger movable in said support; means for normally urging the same in its striking direction; a cam rigidly mounted on said shaft for intermittently withdrawing said plunger; and 90 means for revolving said shaft.

Signed by me, at Chicago, Illinois, this 26th day of July, 1898.

GEORGE A. GAGE.
